UNITED STATES PATENT OFFICE.

CHARLES A. CAMPBELL, OF WATERTOWN, NEW YORK.

LUBRICATING DEVICE.

1,402,051.

Specification of Letters Patent. Patented Jan. 3, 1922.

Application filed June 21, 1921. Serial No. 479,333.

To all whom it may concern:

Be it known that I, CHARLES A. CAMPBELL, a citizen of the United States, residing at Watertown, in the county of Jefferson 5 and State of New York, have invented certain new and useful Improvements in Lubr-
icating Devices, of which the following is a specification.

This invention relates to lubricating de-
vices, and particularly to combined force 10 and gravity feed lubricators for air com-
pressors and other pumps and motors of the
expansible chamber type.

The device operates to feed oil at each 15 compressor piston stroke and derives the power to effect each oil-feeding operation from the pressure fluctuation accompanying such piston stroke. The lubricator thus operates only when the compressor or other 20 connected device operates.

The mechanism includes an oil reservoir 25 and a retarded, multiple-ported valve. This valve acts on a rise of compressor cylinder pressure to admit elastic pressure fluid over the oil in the reservoir, and then traps this 30 pressure fluid. When cylinder pressure falls the valve moves back toward its initial position. In its travel it momentarily opens an oil port, permitting the pressure 35 fluid trapped over the oil to force a small quantity of oil into a delivery passage, and when the valve reaches its initial position the remaining trapped pressure fluid is caused to blow this oil from the delivery 40 passage into the compressor cylinder. This cycle is repeated for each cycle of the pump.

The invention also involves certain features of construction leading to ease of manufacture, fewness of parts and certainty 45 of function.

In the drawings:—

Fig. 1 is a vertical axial section of the complete lubricator with the combined reservoir and valve in its lowest position, the 45 arrows showing the path and direction of air flow when pressure begins to rise in the connected cylinder.

Fig. 2 is a similar view showing the combined reservoir and valve at its upper limit 50 of travel. It is in this position at the time of maximum pressure in the connected cylinder.

Fig. 3 is a similar view showing the combined reservoir and valve moving down-
ward, at the point when oil discharges from 55 the reservoir to the side port in the casing.

Fig. 4 shows the parts in the same position as Fig. 1, but the arrows show the fluid flow at the end of the cycle when pressure in the connected cylinder is dying away and 60 oil is flowing from the lubricator to the cylinder.

Fig. 5 is a half elevation and half section of the combined reservoir and valve.

Fig. 6 is a half elevation and half section 65 of the ported liner in which the combined valve and reservoir is guided.

The device is housed in a hollow cylindrical casing 11 open at its upper end and closed at its lower end except for the threaded opening 12 into which is screwed the nipple 13 having a choke port 14. The size of choke port 14 controls the rate of oil feed and I contemplate the use of interchangeable nipples 13 having different sizes 75 of choke port. A union 15 is provided to connect nipple 13 to a pipe leading to the pump cylinder (not shown). This pipe conducts oil from the lubricator to the cylinder and also transmits pressure fluctuations be- 80 tween the cylinder and lubricator.

The casing is connected to any suitable support by studs or machine screws (not shown) threaded into the holes 16.

The open upper end of casing 11 is closed 85 by a cap 17 having a central aperture, the cap being held in place by screws 18, and a gasket 19 being inserted to seal the joint. The cylinder is lined by a ported cylindrical bushing 20 which seats at its lower 90 end on a gasket 21 and at its upper end against a portion of gasket 19. The bushing 20 is thus in effect the same as if integral with casing 11, but the use of a separate bushing simplifies the formation of 95 the ports and the selection of materials.

The bushing 20 is formed with an inwardly projecting stop-flange 22 at its lower end and with a side port 23 which connects air port 24 and oil port 25, both near the top 100 of bushing 20 with a port 26 near the lower end of the bushing.

A cup-shaped member 27 which combines the functions of the oil reservoir, actuating piston and distributing valve is vertically 105 slidable in bushing 20 between limits defined by its collision with flange 22 and cap 17. The member 27 is open at its upper end and has at its lower end a skirt 28 extending below partition 29 which serves as the bottom 110 of oil reservoir 30.

Through the skirt 28 extend a series of

ports 31 which lead to an annular groove 32. The port 26 registers with groove 32 in the lowermost position of member 27, is uncovered by member 27 in its uppermost position, and is blanked in all other (intermediate) positions of said members.

- An oil port 33 extends from a point near the bottom of oil reservoir 30 to annular oil groove 34 near the upper end of member 27.
- 10 Groove 34 is so positioned that it registers with oil port 25 of bushing 20 in an intermediate position of member 27 (see Fig. 3), port 25 and groove 34 being both blanked in all other positions (see Figs. 1 and 2).
- 15 Air port 24 is open in the lowermost position of member 27 and is blanked in all other positions.

The central aperture in cap 17 is closed by filling plug 35 which is threaded therein 20 and seals against gasket 36. Plug 35 carries a guide rod 37 on which is slidably mounted the retarding sleeve 38. Complete separation of sleeve 38 and rod 37 is prevented by the pin and slot connection 39.

25 Sleeve 38 is urged downward by coil spring 40 surrounding rod 37 and interposed between the flanged upper end of sleeve 38 and the lower face of plug 35.

With the parts assembled as shown in Fig. 30 1 spring 40 holds sleeve 38 against the upper face of partition 29 and thus acts continually to urge member 27 toward its lowermost position. Groove 41 in the lower end of sleeve 38 permits oil flow to and from the interior of sleeve 38.

Assume that the lubricator is connected by a pipe to the cylinder of a compressor. At the end of the suction stroke the parts of the lubricator will be in the position 40 shown in Fig. 1, and as the compression stroke commences air will flow through ports 31, 26, 23 and 24 to the space in the top of the lubricator above the oil contained in reservoir 30. During this flow the retard 45 spring 40 is holding member 27 down against the air pressure acting on the lower side of partition 29. Before the completion of the compression stroke of the compressor, member 27 will shift to its uppermost position, 50 the spring 40 being overpowered by the effective upward pressure on partition 29.

In the position shown in Fig. 2 the oil in reservoir 30 is under elastic fluid pressure, ports 24 and 25 are both blanked, and port 55 23 is vented through port 26 which is cleared by skirt 28.

After pressure in the compressor has begun to fall member 27 will start downward impelled partly by spring 40 and partly by 60 the pressure fluid trapped above the oil.

In its travel it passes through the position shown in Fig. 3 in which position port 26 is blanked and port 25 registers with groove 34. Since port 23 was vented in the 65 uppermost position of member 27, the pres-

sure fluid acting on the oil in reservoir 30 forces oil through port 33, groove 34 and port 25 to fill or partly fill port 23.

The effect of retard spring 40 is to cause member 27 to reach its lowest position early 70 in the suction stroke of the compressor, and the remaining pressure fluid above member 27 then acts through port 24 to blow the oil out of port 23 through port 26, groove 32 and ports 31. Thence it is carried partly 75 by gravity and partly by the air current to the compressor cylinder.

The cycle above described is repeated for each cycle of the compressor.

While I prefer to adjust the oil feeding 80 action of the lubricator by changing the length or diameter (or both) of the choke port 14, the adjustment can be made in other ways. The result can be accomplished by changing the number or size of ports 31, by 85 changing the size of port 8, or by changing the length or diameter of the pipe connecting the lubricator and pump cylinder. All these methods of adjustment have in common the idea of varying a throttling effect 90 on pressure fluid surging between the compressor and pump, and in their broad aspects are equivalents.

What is claimed is:—

1. In a lubricator for cylinders, the combination of an oil reservoir; a ported casing; a ported piston mounted to reciprocate in said casing; resilient means urging said piston in one direction; and a connection serving to cause pressure fluid from the 95 lubricated cylinder to act against said piston in opposition to said resilient means and move said piston in response to variations of pressure in the lubricated cylinder; the ports in said piston and casing coacting on an initial rise in pressure to admit pressure fluid to said reservoir, on greater rise of pressure to trap said pressure fluid in said reservoir, on fall of pressure to release a definite quantity of oil from said reservoir; and on further fall of pressure to direct said trapped pressure fluid against said released quantity of oil to expel the same from the lubricator. 100

2. In a lubricator for cylinders, the combination of an oil reservoir; a casing provided with an oil receiving passage and ports connecting therewith; a ported piston mounted to reciprocate in said casing; resilient means urging said piston in one direction; and a connection serving to cause pressure fluid from the lubricated cylinder to 115

act against said piston in opposition to said resilient means, and move said piston in response to variation of pressure in the lubricated cylinder, the ports in said piston and

casing coacting on an initial rise in pressure to admit pressure fluid to said reservoir, on a greater rise of pressure to trap said

pressure fluid in said reservoir and vent said oil receiving passage, on fall of pressure to 120

act against said piston in opposition to said resilient means, and move said piston in response to variation of pressure in the lubricated cylinder, the ports in said piston and

casing coacting on an initial rise in pressure to admit pressure fluid to said reservoir, on a greater rise of pressure to trap said

pressure fluid in said reservoir and vent said oil receiving passage, on fall of pressure to 125

act against said piston in opposition to said resilient means, and move said piston in response to variation of pressure in the lubricated cylinder, the ports in said piston and

casing coacting on an initial rise in pressure to admit pressure fluid to said reservoir, on a greater rise of pressure to trap said

pressure fluid in said reservoir and vent said oil receiving passage, on fall of pressure to 130

- release oil from said reservoir to said oil receiving passage, and on further fall of pressure to cut off oil from said reservoir and direct said trapped pressure fluid into 5 said oil receiving passage to expel the contained oil from the lubricator.
3. In a lubricator for cylinders, the combination of a ported casing; a combined reservoir and ported piston mounted to reciprocate in said casing; a spring urging said piston in one direction; and a connection serving to cause pressure fluid from the lubricated cylinder to act against said piston in opposition to said spring and move said 10 piston in response to variations of pressure in the lubricated cylinder, the ports in said piston and casing coacting on an initial rise of pressure to admit pressure fluid to said reservoir, on greater rise of pressure to trap said pressure fluid in said reservoir, and on 15 fall of pressure, first to release a small quantity of oil from said reservoir and then on further fall of pressure to direct said trapped pressure fluid against said released oil to 20 25 expel the same from the lubricator.
4. In a lubricator for cylinders, the combination of a ported casing; a cup-shaped ported piston open at its upper end, adapted to serve as an oil reservoir; and mounted to reciprocate in said casing; a spring urging 30 35 said piston downward; a connection adapted to cause pressure fluid from the lubricated cylinder to act against the lower side of said piston to move the same in response to variations of pressure in the lubricated cylinder, the ports of said piston and casing coacting on an initial rise of pressure to admit pressure fluid above said piston, on greater rise of pressure to trap said pressure fluid above said piston and on fall of pressure first to 40 discharge a small quantity of oil from said reservoir by the action of said trapped pressure fluid and then on further fall of pressure to cut off said discharge and direct said pressure fluid against said discharged oil and 45 blow the same into said connection.
5. In a lubricator for cylinders, the combination of a ported casing; a cup-shaped piston open at its upper end, adapted to serve as an oil reservoir and having ports 50 one of which is an oil port leading from near the bottom of the reservoir to a point above the oil level in said reservoir; a spring urging said piston downward; and a connection serving to cause pressure fluid from the lubricated cylinder to act against the lower face of said piston and move said piston in response to pressure variations in said cylinder, the ports in said piston and casing coacting on an initial rise in pressure to admit 55 pressure fluid above said piston, upon continued rise in pressure to trap said pressure fluid above said piston, and upon fall of pressure first to permit oil to discharge from said oil port under the pressure of said 60 65 trapped pressure fluid, and then to cut off said discharge and release said trapped pressure fluid over said discharged oil to blow said oil from the lubricator into said connection.

70
In testimony whereof I have signed my name to this specification.

CHARLES A. CAMPBELL.
